UNITED STATES PATENT OFFICE.

HEINRICH GERHARD WULFF, OF EILENBURG, GERMANY.

MEANS FOR INTERMITTENTLY ROTATING TABLES.

No. 823,249.

Specification of Letters Patent.

Patented June 12, 1906.

Application filed July 26, 1905. Serial No. 271,337.

To all whom it may concern:

Be it known that I, HEINRICH GERHARD WULFF, a subject of the King of Prussia, German Emperor, residing at Eilenburg, 5 Prussia, Germany, have invented a new and useful Improved Means for Intermittently Rotating Tables, of which the following is a full, clear, and exact specification.

The present invention relates to means for 10 intermittently rotating tables, principally such as are used in connection with machine-tools, and more particularly with machines for pressing artificial stones and the like; and the invention consists of the details of construction hereinafter set forth, and particularly pointed out in the claims.

In order to render the present specification easily intelligible, reference is had to the accompanying drawings, in which similar letters 20 of reference denote similar parts throughout the several views.

Figure 1 is a side elevation of the device; Fig. 2, a plan; and Fig. 3, a part side elevation, partly in section.

25 The table *a* to be intermittently rotated is mounted to rotate loosely on the shoulder of a vertical shaft *c*, on which it rests with the hub *b*. Loosely mounted and supported in the vertical direction on the larger part of the said 30 shaft *c*, beneath the table *a*, is an arm *e*, to the free end of which is attached, by means of a universal joint *g*, one end of a connecting-rod *k*, the other end of which is connected to the crank-pin *h* of a crank-disk *i*. Arranged in 35 a circle the center of which coincides with the center of the shaft *c* on the under side of the table *a* is a series of ratchet-like recesses *d*, the forward ends of which are cut vertically into the under side of the table, while the 40 rear ends taper gradually off toward the under surface of the said table. These notches are made at a distance apart corresponding to the stroke of the rod *k*, or approximately so, and to the stroke the table is to make at 45 each intermittent movement. In the upper face of the end of the arm *e* an upwardly-spring-pressed coupling-pin *f* is provided, which is adapted to be normally spring-pressed against the under surface of the table 50 and is arranged at a radius corresponding to that of the center line of all the ratchet-notches *d*.

The operation of the device is very simple. When the crank-disk *i* is rotated, the arm *e* 55 will be rocked by the connecting-rod *k* to an extent corresponding to the double throw of

the crank-pin *h*. The coupling-pin *f*, being in engagement with the vertical end of one of the notches *d* when the arm *e* is at the commencement of its stroke will obviously pull 60 the table round by the action of the rod *k* and the universal joint *g* until the crank-pin has performed its full stroke, when the table will be arrested by any suitable known means and the arm *e* commences its return stroke, the 65 coupling-pin *f* sliding gradually out of the notch in which it has been and compressing its spring. It will then slide along the under surface of the table until the arm *e* has completed its stroke backward, when it will 70 spring into the next notch *d* at the rear and again pull the table round the desired distance.

Obviously the pin might be actuated by a weight instead of the spring; as illustrated.

By means of the present invention the 75 means for intermittently rotating a table are very considerably simplified, and a comparatively long travel at each movement may be attained without having to employ long guide-ways and operating-arms, as has hitherto 80 been the case.

I claim—

1. A device for intermittently rotating a pivotally-supported table having ratchet-like depressions, said device comprising an 85 arm loosely mounted on the pivot of the table, a crank-disk, a connecting-rod attached to said disk, a universal-joint connection between said arm and said connecting-rod, and means on the free end of the arm to 90 engage with the aforesaid ratchet-like depressions and move the table at each reciprocation of the said arm.

2. A device for intermittently rotating a pivotally-supported table having ratchet-like depressions, said device comprising an 95 arm loosely mounted on the pivot of the table, a crank-disk, a connecting-rod attached to said disk, a universal-joint connection between said arm and said connecting-rod, and a spring-pressed pin mounted on the 100 free end of the arm to engage with the aforesaid ratchet-like depressions and move the table at each reciprocation of the said arm substantially as described.

In testimony whereof I affix my signature 105 in the presence of two witnesses

HEINRICH GERHARD WULFF.
